UNITED STATES PATENT OFFICE.

JOSEPH C. KNIGHT, OF BROCKTON, MASSACHUSETTS.

PERFORATING MACHINE.

Application filed May 29, 1925. Serial No. 33,795.

This invention relates to a machine for ornamenting shoe uppers, or parts thereof, by cutting out small portions of the material to form orifices therein, the machine including a reciprocating platen and a group of punches supported in the path of the platen and adapted to cooperate therewith in cutting out portions of the material of a shoe upper interposed between the punches and the platen.

The chief object of the invention is to provide a perforating machine adapted to be advantageously operated to perforate the several parts of a fitted upper, after said parts have been assembled and stitched together.

A machine embodying the invention includes an anvil supporting the usual punches, in position to cooperate with the platen, and movable on a fixed supporting bed crosswise of the path of the platen to locate the punches under various parts of the plunger, and to permit the withdrawal of the punches from the path of the plunger.

The anvil is provided with a guide element centrally located between opposite lateral sides of the anvil, and the supporting bed is provided with a complementary guide element, centrally located between opposite lateral edges of the bed and between the lateral sides of the anvil. The arrangement of said guide elements is such that anvils of different sizes and shapes may be used interchangeably on the same bed, without change or adaptation of either of the guide elements, said elements being medially arranged relative to the sides of the anvil and the edges of the bed, so that hands grasping the work at opposite sides of the anvil are not obstructed by the guide elements. The machine frame and the anvil are so formed that the operator's hands, while located below and out of the path of the plunger and below the top of the anvil and the punches thereon, may grasp marginal portions of the upper and hold the latter in the different positions relative to the platen and the punches, required to cause the perforation of different parts of a fitted upper by a series of operations, the operator's hands being so located that they are not liable to be injured during the punching operation, and are freely movable to hold the grasped marginal portions of the upper in the different positions required.

Other objects of the invention, and means for accomplishing the same, will appear hereinafter.

Of the accompanying drawings forming a part of this specification,

Figure 1 is a front elevation of a perforating machine embodying the invention, this figure showing an anvil of minimum width.

Figure 2 is a view similar to the lower portion of Figure 1, showing a wider anvil.

Figure 3 is a section on line 3—3 of Figure 1.

Figure 4 is a side elevation, showing the machine on a smaller scale, and an adjunct thereto described, associated therewith.

Figure 5 shows in perspective the adjunct shown by Figure 4.

Figure 6 is a fragmentary section on line 6—6 of Figure 5.

Figure 7 is a fragmentary section on line 7—7 of Figure 6.

The same reference characters indicate the same parts in all of the figures.

The frame of the machine designated as a whole by 12, is provided with guides in which a reciprocating platen 13 is movable. The guides here shown include fixed plates or gibs 14 (Figure 1), and the plunger is fixed to a slide or head 15, engaged with the guides.

Extending under the platen is a fixed bed, arranged in a plane substantially at right angles with the path of the platen. The bed may include an inner portion 16, integral with the frame, and an outer portion 16^a, formed as a shelf or bracket, fixed to the frame as shown by Figure 3.

Movable on the bed is an anvil 17, to the upper or head portion of which is detachably secured a block or plate 18, carrying the usual tubular or hollow punches 19, adapted to cooperate with the platen in cutting orifices in an upper, the form and arrangement of the orifices being determined by the form and arrangement of the punches. The block also carries the usual yielding stripper plate 20, adapted to be depressed by the platen and to strip the work from the punches when the platen rises. It will be understood that there is nothing new with me in the punching and stripping means, and that blocks 18 of various sizes and having various forms and arrangements of punches may be used interchangeably.

The bed and the anvil are provided with being bent downward by the operator's
complemental guide elements, medially arranged relative to opposite lateral edges of hands and securely confined during the
the bed, and opposite lateral sides of the punching operation.
5 anvil, and adapted and arranged to guide The platen may be reciprocated by any
the anvil in a path parallel with the bed suitable mechanism. The preferred mech- 70
and substantially at right angles with the a-nism includes a driving shaft 31 (Figure 3)
path of the platen, the preferred guide journaled in bearings on the frame and pro-
elements being a rib or track 21, fixed to and vided with an eccentric 32, an eccentric link
10 centrally arranged on the bed, between the 33, having a ring 34 embracing the eccentric,
opposite edges thereof, and extending from and a pair of toggle members 35, pivotally 75
the outer to the inner end thereof, and a jointed to each other and to the eccentric
groove 22, formed in the base portion of link 33 at 36, the lower toggle member being
the anvil between opposite sides thereof and jointed at 37 to the platen-carrying slide 15,
15 having a sliding fit on the track 21. The while the upper toggle member is jointed at
central or medial location of said guide 38 to a pressure-adjusting block 39. Said 80
elements midway between the lateral sides of block is adjustable on an inclined internal
the anvil and the lateral edges of the bed guiding face 40, on the frame, and may be
ensures an equal bearing of the anvil on the adjusted outward or inward from the position
20 bed at each side of the guide elements, as shown by Figures 1 and 2, and enables anvils
of different widths to be used interchangeably, so that a relatively narrow anvil may be used as shown by Figure 1, and a wider
25 anvil as shown by Figure 2. The medial location of the guide elements also prevents interference of said guide elements with hands grasping the work, the guide elements being internally arranged so that they do not obstruct spaces for the hands at opposite
30 sides of the anvil.

The frame is preferably formed with a recess, designated by the numeral 23 in Figures 1 and 2, formed to receive the anvil, 35 and of such size that spaces are formed at opposite sides of the anvil in which the hands *h* of the operator may be inserted, as indicated by dotted lines in Figure 1, said spaces permitting the location of the hands
40 below the top of the anvil, while marginal portions of an upper extending across the punches are grasped by the hands. This location of the hands prevents liability of injury thereto by the punching and stripping means, and by the platen during the
45 operation of the machine.

To additionally guard against such injury, I provide hand guards 24, overhanging the spaces at opposite sides of the anvil, 50 as shown by Figure 1, and preferably composed of metal plates having shanks 25, adjustably secured by set screws 26 to a transverse rod 27. Said rod is secured by set screws 28 to fixed ears 29 (Figure 1) on the frame. The hand guards are adjustable on the rod, to conform to the width of the anvil, as indicated by Figures 1 and 2. The guards render it impossible for the operator to insert a finger between the stripper plate and
55 the platen.

It will now be seen that a fitted upper may be advantageously held in various positions on the anvil, to cause the formation of orifices in any desired part or parts thereof, 60 opposite marginal portions of the upper
65

being bent downward by the operator's hands and securely confined during the punching operation.
The platen may be reciprocated by any suitable mechanism. The preferred mech- 70 a-nism includes a driving shaft 31 (Figure 3)
journaled in bearings on the frame and pro-
vided with an eccentric 32, an eccentric link
33, having a ring 34 embracing the eccentric,
and a pair of toggle members 35, pivotally 75
jointed to each other and to the eccentric
link 33 at 36, the lower toggle member being
jointed at 37 to the platen-carrying slide 15,
while the upper toggle member is jointed at
38 to a pressure-adjusting block 39. Said 80
block is adjustable on an inclined internal
guiding face 40, on the frame, and may be
adjusted outward or inward from the position
shown by Figure 3, by an adjusting
screw 41, engaged with a tapped orifice in 85
the block. The screw is provided with an
unthreaded outer portion 42, having a per-
ipheral groove 43, and a hand wheel 44.
A fixed plate 45 on the frame, has a slot 46,
the closed end of which engages the groove 90
43, and prevents endwise movement of the
adjusting screw when the latter is rotated.
When the adjusting screw is turned, it causes
an endwise movement of the block 39. This
movement is caused by the inclination of the 95
guiding face 40, to slightly raise or lower
the pivot 38, and thus slightly vary the
throw of the platen, so that the degree of
pressure of the platen on the punches may
be minutely regulated, without moving the 100
platen edgewise and shifting it from its pre-
determined path. The adjusting screw 41
is provided with a reduced extension 47,
having a nut 48, constituting an adjustable 105
abutment for a spring 49, adapted to exert
endwise pressure on the screw and hold the
outer edge of the groove 43 in contact with
the plate 45, the object being to compensate
for wear of the outer edge of the groove.

The machine may be provided with any suitable means for feeding the usual paper facing strip 50 across the acting face of the platen, said means, in this instance, including a corrugated feed roll 51, journaled in bearings on the frame and rotated step by step by any suitable connections between the roll and the driving shaft 31, and an idle corrugated top roll 52, pressed by springs 53 against one side of the used portion of the facing strip passing from the platen between the rolls. The facing strip is originally wound to form a supply roll 50^a from which the unused portion of the strip unwinds and passes over suitable guides to and across the platen. The used portion passing from the feed rolls is gradually accumulated in the form of a rewound roll 50^b.

I provide the machine with an adjunct, 115
adapted to loosely support and permit the 120
unwinding of the strip from the supply roll 125
130

- 50^a, and to cooperate with the driving shaft 31 in winding the used portion to form the roll 50^b and guide the strip in its progressive movement. Said adjunct shown by 5 Figures 4 and 5, comprises a fixed standard 55, located behind the machine, a spindle 56, fixed to the standard at 57 and projecting laterally therefrom, and adapted to support the supply roll 50^a, a winding shaft 58, journaled in a bearing 59 in the standard, and having a pulley 60, connected by a driving belt 61 with a pulley on the driving shaft, a pair of collars 61^a, adjustably secured by set screws 62 to the winding shaft and provided 10 with fingers 63, adapted to engage the free end of the used portion of the facing strip, and a pair of elongated guiding arms 64, adjustably secured by set screws 65 to the spindle 56. Said arms bear loosely on the 15 collars 61^a, and are confined laterally by the shoulders 62^a thereof, as indicated by Figures 5, 6 and 7. The guiding arms bear on opposite ends of the supply roll 50^a, and on opposite ends of the rewound roll 50^b to prevent endwise displacement of said rolls. The rotation of the winding shaft causes the 20 formation of the roll 50^b thereon.
- It will be seen that the bed and anvil are characterized by the fact that each is provided with a single internal or centrally arranged track or guide element, said elements being interengaged at the longitudinal central portion of the bed and anvil, so that the bed, provided with the internal guide element 21, is adapted to cooperate with either of a plurality of anvils, each having a complementary guide element 22, without change or adaptation of the guide elements. In 25 other words, the bed having the internal centrally arranged guide or track element 21, is adapted to support and guide a relatively narrow anvil, as shown by Figure 1, or a wider anvil, as shown by Figure 2, each anvil having a complementary centrally arranged internal guide element 22.
- The substitution of one anvil for another requires no change or modification of the guide elements. It is my practice to provide with each machine a plurality of interchangeable anvils, each equipped with a die block 18, having suitable punches and the usual parts cooperating therewith, each anvil differing from the others in the form and arrangement of its punches, and each having an internal centrally arranged guide element 22. The machine is therefore adapted to be quickly and conveniently altered to enable it to produce different designs, and ornament uppers of different sizes and 30 styles, by the simple operation of removing the anvil and substituting another therefor, without change or adaptation of the guide elements.
- To prevent the possibility of injury to the cutting edges of the punches by contact with 35 the metal of the platen, in case the punches cut entirely through the facing strip 50, I provide the platen with a non-metallic facing layer 67, preferably of dense fibrous material, such as vulcanized fiber. The facing layer 70 may be attached to the platen by suitable means, such as screws inserted in its corner portions and engaged with tapped orifices in the platen, so that the layer is removable and renewable. The facing layer 75 composed of material which is softer than that of the punches, prevents possibility of contact between the punches and the relatively hard material of the body of the platen, in case the platen is improperly adjusted, so that the punches pass entirely through the facing strip 50, a proper adjustment of the platen being one which causes the punches to only partly penetrate the strip 50.
- The forward ends of the hand guards 24 are located outside the path of the plunger. The guards face downward and are extended inward from their forward ends sufficiently to protect the operator's fingers when the 80 anvil is in different operative positions. The means for adjustably supporting the hand guards may include inner shanks 25^a (Figure 4), formed on the guards and having studs 25^b slidable in the fixed ears 29.
- I believe myself to be the first to provide for use in a perforating or cutting-out machine an element comprising a die-block 85 equipped with the usual punches or cutting-out dies, and the usual accessories including 90 a stripper plate, and an individual anvil to which the die-block is fixed, the anvil being provided with a centrally or medially located guide element adapted to be movably and separably engaged with a fixed complementary centrally located guide element 100 on the frame of the machine, so that the machine may be adapted to perform different kinds of work by removing an anvil, the die-block of which has punches adapted to produce a given ornamentation, and substituting therefor another anvil carrying a differently formed die-block.
- I claim:
1. A perforating machine comprising a 115 frame having fixed platen guides; a reciprocating platen movable in said guides; a fixed bed arranged in a plane substantially at right angles with the path of the platen, and extending under the latter, and an anvil manually movable on the bed and provided with punches adapted to cooperate with the platen, the bed and anvil being provided with complementary guide elements, adapted and arranged to guide the anvil in 120 a path parallel with the plane of the bed, and permit anvils of different widths to be used interchangeably with the bed, without change or adaptation of the guide elements, the frame, the bed, and the anvil being 125

- 4 formed and arranged to provide spaces at the opposite sides of the anvil, and below the upper surface thereof for hands holding the work.
2. A perforating machine comprising a frame having fixed platen guides; a reciprocating platen movable in said guides; a fixed bed arranged in a plane substantially at right angles with the path of the platen, and extending under the latter, and an anvil manually movable on the bed and provided with punches adapted to cooperate with the platen, the bed and anvil being provided with complementary guide elements, 10 adapted and arranged to guide the anvil in a path parallel with the plane of the bed, and permit anvils of different widths to be used interchangeably with the bed, without change or adaptation of the guide elements, 15 the frame, the bed, and the anvil being formed and arranged to provide spaces at the opposite sides of the anvil, and below the upper surface thereof for hands holding the work, the bed and the base of the 20 anvil being each extended laterally in opposite directions from said guiding element.
3. A perforating machine comprising a frame having fixed platen guides; a reciprocating platen movable in said guides; a fixed bed arranged in a plane substantially at right angles with the path of the platen, and extending under the latter, an anvil manually movable on the bed and provided 25 with punches adapted to cooperate with the platen, the bed and anvil being provided with complementary guide elements, adapted and arranged to guide the anvil in a path parallel with the plane of the bed, the 30 frame, the bed and the anvil being formed and arranged to provide spaces at the opposite sides of the anvil, and below the upper surface thereof for hands holding the work; and downwardly facing hand guards supported by the frame above the bed and 35 overhanging said spaces, said guards being extended inward from their forward ends to protect the operator's fingers when the anvil is in different operative positions.
4. A perforating machine comprising a frame having fixed platen guides; a reciprocating platen movable in said guides; a fixed bed arranged in a plane substantially at right angles with the path of the platen, and extending under the latter, an anvil 40 manually movable on the bed and provided with punches adapted to cooperate with the platen, the bed and anvil being provided with complementary guide elements, adapted and arranged to guide the anvil in a path 45 parallel with the plane of the bed, and permit anvils of different widths to be used interchangeably with the bed, without change or adaptation of the guide elements, 50 means being provided for laterally adjusting the guards so that they may conform in
- position to anvils of different widths, the frame, the bed, and the anvil being formed and arranged to provide spaces at the opposite sides of the anvil, and below the upper surface thereof for hands holding the work; 55 and downwardly facing hand guards supported by the frame above the bed and overhanging said spaces, said guards being extended inward from the forward ends to protect the operator's fingers when the anvil is in different operative positions.
5. A perforating machine comprising a frame having fixed platen guides; a reciprocating platen movable in said guides; a fixed bed arranged in a plane substantially 60 at right angles with the path of the platen, and extending under the latter, an anvil manually movable on the bed and provided with punches adapted to cooperate with the platen, the bed and anvil being provided with complementary guide elements, adapted and arranged to guide the anvil in a path 65 parallel with the plane of the bed, and permit anvils of different widths to be used interchangeably with the bed, without change or adaptation of the guide elements, 70 the frame, the bed, and the anvil being formed and arranged to provide spaces at the opposite sides of the anvil, and below the upper surface thereof for hands holding the work; 75 and downwardly facing hand guards supported by the frame above the bed and overhanging said spaces, said guards being extended inward from their forward ends to protect the operator's fingers when the anvil is in different operative positions.
6. A perforating machine comprising a reciprocating platen movable in fixed guides on the frame of the machine; a fixed bed arranged in a plane substantially at right angles with the path of the platen, and provided with a centrally located internal anvil 80 guide element extending from front to rear of the bed; and an anvil manually movable on the bed and including a base portion having a centrally located complementary internal guide element slidably engaged with the guide element of the bed, and a head portion provided with punches adapted to cooperate with the platen, said guide elements being adapted and arranged to guide the anvil in a path parallel with the plane of the bed, and permit anvils of different widths to be used interchangeably with the bed, without change or adaptation of the 85 guide elements.
7. A perforating machine comprising a frame including platen guides, a bed arranged in a plane substantially at right angles with the guides, and having an anvil 90

- guide element medially located between opposite lateral edges of the bed; a reciprocating platen movable in said platen guides; and an anvil manually movable on the bed 5 and provided with a guide element medially located between opposite sides of the anvil, and engaging the aforesaid guide element on the bed, thus providing spaces at opposite sides of the anvil for the operator's hands.
10. 8. A perforating machine comprising a frame having fixed platen guides and a fixed inclined block-guiding face, a platen movable in a predetermined path in said guides, a group of punches, means for supporting the punches to cause the cooperation thereof with the platen, and platen-reciprocating mechanism having means for varying the movement of the platen toward the punches without shifting the platen from its predetermined path, said mechanism including a block slideable on said inclined guiding face, pivotally connected toggle members, one jointed to the block and the other to the platen, means for operating said toggle members to reciprocate the platen, and means for adjusting the block on the inclined guiding face to vary the movement of the platen toward the punches.
9. In a perforating machine which includes a platen, mechanism including a driving shaft for reciprocating the platen, punches supported in the path of the platen and adapted to cooperate therewith, and means for feeding a paper facing strip across the acting face of the platen; an adjunct adapted to support and permit the unwinding of a rolled supply portion of said strip; and to cooperate with the driving shaft in winding the used portion of the strip, and 30 guide the strip in its progressive movement across the platen, said adjunct comprising a fixed standard located behind the machine;
- a spindle fixed to and projecting laterally from the standard and adapted to support the rolled supply portion, a winding shaft 45 journaled in and projecting laterally from the standard and having a pulley connected by a driving belt with the driving shaft; a pair of shouldered collars adjustably secured to the shaft and having means for 50 engaging the free end of the used portion, and a pair of elongated guiding arms adjustably secured to the spindle, bearing loosely on the collars and confined laterally by the shoulders thereof, said guiding arms 55 bearing on the opposite ends of the rolled supply portion, and on the opposite ends of the rolled used portion, to prevent endwise displacement of said rolled portions.
10. In a perforating machine, in combination, a reciprocating platen provided with a facing layer of relatively soft material, detachably secured to the body of the platen and constituting the acting face thereof, means for feeding a paper facing strip 60 across the facing layer, punches supported in the path of the platen, and means for adjusting the platen relative to the punches, the facing layer being composed of material softer than that of the punches, and preventing contact of the punches with the body of the platen, in case of improper adjustment of the platen.
11. In a perforating machine, an anvil provided at its upper portion with punches, 75 and at its base portion with a guide element medially located between opposite lateral sides of the anvil, and adapted to cooperate with a fixed guide element medially located between opposite lateral edges of an anvil- 80 supporting bed.

In testimony whereof I have affixed my signature.

JOSEPH C. KNIGHT.

- guide element medially located between opposite lateral edges of the bed; a reciprocating platen movable in said platen guides; and an anvil manually movable on the bed 5 and provided with a guide element medially located between opposite sides of the anvil, and engaging the aforesaid guide element on the bed, thus providing spaces at opposite sides of the anvil for the operator's hands.
8. A perforating machine comprising a frame having fixed platen guides and a fixed inclined block-guiding face, a platen movable in a predetermined path in said guides, a group of punches, means for supporting the punches to cause the cooperation thereof with the platen, and platen-reciprocating mechanism having means for varying the movement of the platen toward the punches without shifting the platen from its predetermined path, said mechanism including a block slideable on said inclined guiding face, pivotally connected toggle members, one jointed to the block and the other to the platen, means for operating said toggle members to reciprocate the platen, and means for adjusting the block on the inclined guiding face to vary the movement of the platen toward the punches.
9. In a perforating machine which includes a platen, mechanism including a driving shaft for reciprocating the platen, punches supported in the path of the platen and adapted to cooperate therewith, and means for feeding a paper facing strip across the acting face of the platen; an adjunct adapted to support and permit the unwinding of a rolled supply portion of said strip; and to cooperate with the driving shaft in winding the used portion of the strip, and 40 guide the strip in its progressive movement across the platen, said adjunct comprising a fixed standard located behind the machine;
- a spindle fixed to and projecting laterally from the standard and adapted to support the rolled supply portion, a winding shaft 45 journaled in and projecting laterally from the standard and having a pulley connected by a driving belt with the driving shaft; a pair of shou'dered collars adjustably secured to the shaft and having means for 50 engaging the free end of the used portion, and a pair of elongated guiding arms adjustably secured to the spindle, bearing loosely on the collars and confined laterally by the shoulders thereof, said guiding arms 55 bearing on the opposite ends of the rolled supply portion, and on the opposite ends of the rolled used portion, to prevent endwise displacement of said rolled portions.
10. In a perforating machine, in combination, a reciprocating platen provided with a facing layer of relatively soft material, detachably secured to the body of the platen and constituting the acting face thereof, means for feeding a paper facing strip 60 across the facing layer, punches supported in the path of the platen, and means for adjusting the platen relative to the punches, the facing layer being composed of material softer than that of the punches, and preventing contact of the punches with the body of the platen, in case of improper adjustment of the platen.
11. In a perforating machine, an anvil provided at its upper portion with punches, 75 and at its base portion with a guide element medially located between opposite lateral sides of the anvil, and adapted to cooperate with a fixed guide element medially located between opposite lateral edges of an anvil- 80 supporting bed.
- In testimony whereof I have affixed my signature.
